UNITED STATES PATENT OFFICE.

FRANK W. BARROWS, OF LEOMINSTER, MASSACHUSETTS.

MUSIC-SHEET HOLDER.

No. 830,197.

Specification of Letters Patent.

Patented Sept. 4, 1906.

Application filed April 15, 1905. Serial No. 255,739.

To all whom it may concern:

Be it known that I, FRANK W. BARROWS, a citizen of the United States, residing at Leominster, in the county of Worcester and 5 State of Massachusetts, have invented certain new and useful Improvements in Music-Sheet Holders, of which the following is a specification.

As at present constructed the music used 10 by bandsmen is contained in books or on loose sheets that are secured to the instrument by means of a spring-clasp mounted on the instrument. This means of holding the music is unsatisfactory because the prongs of the 15 clasp hide some of the notes in the score and also if there is a breeze the corners of the leaves are blown over so as to hide a part of the selection. Another disadvantage of the old style of music-holder is that whenever the 20 selection is to be changed the musician has to take the music out of the holder, place the instrument under his arm, turn over the leaves of the book containing the music until the selection is found, and then replace the 25 music in the holder.

My invention relates to the improvement 30 of these devices; and it consists of casing that may be mounted on the music-holding standard so that the prongs do not rest on the music- 35 page, while the music is printed on separate leaves, with numbered, lettered, or otherwise designated tabs on their upper edge to answer for finger-holds to handle the leaf, as well as for indexes for ready reference. A spring 40 and pivoted clasp is secured to the top of the casing and is adapted to hold the leaves in the casing. This construction permits of changing the selection without removing the music-holder from the instrument, and the 45 music-leaves are so held while the instrument is being played that all the notes are visible and are not disturbed by the wind.

My invention will be more particularly described hereinafter and illustrated in the accompanying drawings, in which—

Figure 1 is a front view of my improved music-sheet holder, showing it secured to the standard usually employed for this purpose and the music-sheets in position; and Fig. 2, 50 a view in cross-section on the line xx of Fig. 1.

In the drawings similar reference characters indicate corresponding parts throughout both views.

A represents a rectangular casing consisting of an upright back B, a flange C, extending 55 out from the lower edge of the back B, and

flanges D, extending from the side edges thereof. Flange C is formed with a slot c to receive the stationary portion E of the music-holder F usually employed by bandsmen, the 60 holder being turned around so that the clamp G engages the back B and does not hide any of the notes on the music-score.

The side flanges D are formed with inwardly-extending lips H, which hold the side 65 edges of the sheets of music I, while at the top of the back portion B is secured a pivoted clasp J to hold the top edges of said sheets I. Each of the sheets I is separately removable 70 from the casing A and have integral therewith or secured thereto tabs K, having designating characters, such as numerals or letters, thereon for ready reference. In the drawings the designating characters are shown to be numerals and the tabs are so arranged that the numerals read from "1" to 75 "10" from left to right along the top edge of the sheets. Should more than ten sheets be placed in the casing, tabs having the same relative position as tab designated "1" may 80 be designated "11," "21," "31," and so on. Those having the same relative position as tab designated "2" may be designated "12," "22," "32," "42," and so on and the same plan be adopted for each of the other series of 85 tabs.

By my device it will be readily seen that a ready-reference index is secured, and much confusion may be avoided in bands employing my system in looking for the scores of the 90 various numbers of a program, the only thing necessary being a list of the index-numbers of the pieces to be played, or the leader may readily introduce an interpolated piece into his program by announcing the number on 95 the index-tabs of the piece to be interpolated.

Having thus described my invention, what I claim is—

1. In combination with a music-holder comprising a stationary portion and a clamp 100 pivotally secured thereto, a casing consisting of a rectangular back having lateral flanges, one of said flanges being slotted to receive the stationary portion of the music-holder, the clamp engaging the back of the casing, substantially as shown and described.

2. In combination with a music-holder comprising a stationary portion and a clamp 110 pivotally secured thereto, a casing consisting of a rectangular back having lateral flanges extending from three sides thereof, and inwardly-extending lips on two of said flanges,

one of said flanges being slotted to receive the stationary portion of the music-holder, the clamp thereon engaging the back, substantially as shown and described.

- 5 3. In combination with a music-holder comprising a stationary portion and a clamp pivotally secured thereto, a casing consisting of an upright flat, rectangular back having lateral flanges extending from the lower edge 10 and the two sides thereof, the side flanges having inwardly-extending lips, the flange on the lower edge slotted to receive the stationary

portion of the music-holder, the clamp thereon engaging the back of said casing, and a pivoted clasp secured to the upper edge of 15 the casing, substantially as shown and described.

In testimony whereof I hereto affix my signature in the presence of two witnesses.

FRANK W. BARROWS.
